UNITED STATES PATENT OFFICE.

JOHN A. HEANY, OF PHILADELPHIA, PENNSYLVANIA, ASSIGNOR TO THE TETER-HEANY DEVELOPING COMPANY, OF SAME PLACE AND CHARLESTON, WEST VIRGINIA.

MANUFACTURE OF SOLENOID OR OTHER ELECTRIC COILS.

SPECIFICATION forming part of Letters Patent No. 673,521, dated May 7, 1901.

Application filed February 18, 1901. Serial No. 47,725. (No model.)

To all whom it may concern:

Be it known that I, JOHN A. HEANY, a citizen of the United States, residing at the city of Philadelphia, in the county of Philadelphia and State of Pennsylvania, have invented 5 certain new and useful Improvements in the Manufacture of Solenoid or other Electric Coils, of which the following is a specification.

My invention has relation to the manufacture of windings for a spool or coil to be used for electromagnets, solenoids, and the like; and in such connection it relates to the construction and arrangement of such a winding.

By my present invention the wire, uncovered or naked, is laid upon the spool spirally and properly spaced. The wire is wound tightly upon a sheet or layer of asbestos or similar non-combustible insulating material, so as to preferably sink or embed itself to a 20 more or less extent in said sheet, and then the spaces between the wire coils, as well as the exposed surface of the wire itself, are completely filled and covered with a paste or cement consisting of a non-combustible, insulating, and waterproof mixture, the principal ingredients of which are a suitable oxid and sodium silicate or its equivalent as a binding agent, which mixture readily hardens and unites or cements with the wire and under heat will not be dissipated, peel, or crack 25 off from the wire or lose its other characteristic properties.

The nature and scope of my invention will be more fully understood from the following 35 description, taken in connection with the accompanying drawing, forming part hereof, which illustrates in plan view, partly broken away and partly sectioned, a spool or coil embodying the main features of my invention.

Referring to said drawings, *a* represents the spool of a solenoid-coil, and *a'* its tubular axis, upon which the coil is to be wound.

In carrying out my invention there is first laid around the axis *a'* a sheet or layer *b* of asbestos or similar non-combustible insulating material. Upon this sheet or layer *b* is then spirally wound a bare or uncovered wire *d* to constitute a section of the solenoid-coil. This wire *d* is wound upon the layer *b*, preferably with sufficient tightness or tension as

to partially embed itself in the layer *b*. This serves to keep the coils of the spiral regularly spaced, so that the wire *d* will not cross itself or the coils of the spiral contact. After the wire *d* of one section is wound upon the layer *b* the spaces between its coils, as well as the bare periphery of the wire *d*, are filled and covered with a paste or cement *e*. This paste or cement *e* consists of a mixture which readily hardens, and when hard is non-combustible, impervious to moisture, and forms a good insulation for the wire *d*. It also adheres strongly to the wire and forms a coating which will not peel or chip off, will not disintegrate, and will not lose its non-combustible, waterproof, and insulating qualities when subjected to heat, whether it be heat generated in the wire itself by the passage of the current or generated from an external source. A preferred mixture contains 60 sodium silicate as a binding agent with a metallic oxid, such as manganese oxid added thereto, as a base and the whole formed into a viscous or semifluid mass. The cement *e* may be applied with a brush or any suitable instrument. When one layer or section of the coil has been laid upon the spool and wound, say, from right to left, one end—the inlet end of the wire—projects from an end 65 of the spool. The second section of the coil 70 is next built up in preferably the manner before stated—namely, a sheet or layer *b* is laid on top of the cement coating *e*, the wire *d* is then wound upon the layer *b*, and then coated and covered by cement *e*. The wire *d*, forming the second coiled section, is a continuation 75 of the wire forming the first section; but the second coiled section is wound in a direction reversely to that of the first section—that is, the axis *a'* of the coil always turns in the same 80 direction; but the wire *d* is first fed from right to left to form the first section and then from left to right to form the second section, and so on. These sections are therefore practically continuations of one coil through which the current passes without neutralization to form invariable north and south polarities at the respective ends of the spool. This winding of 85 the second section reversely to the first section insures the passing of the wires of the 90 95 100

second section diagonally over the wires of the first section and prevents, therefore, the coils of either section being forced into the space between the coils of the other section. 5 This preferred manner of construction is carried out, no matter how many sections of wire *d* are laid upon the spool.

Having thus described the nature and object of my invention, what I claim as new, 10 and desire to secure by Letters Patent, is—

1. In a spool or coil for electromagnets and the like, a coil-section of bare wire wound upon a sheet or layer of non-combustible insulating material and a cement covering the 15 bare periphery of the wire and completely filling the spaces between the coils of the section, said cement consisting of a mixture which is non-combustible, impervious to moisture and insulating and adapted to firmly adhere 20 to the wire under all variations of temperature.

2. In a spool or coil for electromagnets and the like, a coil of bare wire embedded between a sheet or layer of asbestos or its equivalent 25 and a non-combustible, moisture-proof and insulating cement, said cement adapted to cover the bare wire and to firmly adhere thereto and to enter the spaces between the coils of said wire.

3. In a spool or coil for electromagnets and the like, a coil of bare wire wound spirally upon a sheet or layer of asbestos or its equivalent under tension sufficient to partially embed the coils in said sheet or layer, and a non-combustible, moisture-proof and insulating cement adapted to completely embed the remaining bare portions of the wire and to enter the spaces between the coils to maintain in conjunction with the sheet or layer the proper spacing of said coils. 35

4. A spool or coil for electromagnets, comprising a series of superposed coil-sections, each section inclosed between two layers or sheets of asbestos or equivalent material, alternate coil-sections being wound reversely 45 upon the preceding section so that the coils of one section diagonally cross the coils of an adjacent section, and a paste or cement interposed between the layers of asbestos inclosing each section and adapted to fill the spaces 50 between the coils of said section.

In testimony whereof I have hereunto set my signature in the presence of two subscribing witnesses.

JOHN A. HEANY.
